US00D959845S

(12) **United States Design Patent** (10) Patent No.: **US D959,845 S**
Okai et al. (45) Date of Patent: ** Aug. 9, 2022

(54) **TRACKING MODULE FOR AN ORAL CARE IMPLEMENT**

(71) Applicant: **Colgate-Palmolive Company**, New York, NY (US)

(72) Inventors: **Takahide Okai**, Highland Park, NJ (US); **GuanMin Sun**, XiaMen (CN)

(73) Assignee: **Colgate-Palmolive Company**, New York, NY (US)

(**) Term: **15 Years**

(21) Appl. No.: **29/697,771**

(22) Filed: **Jul. 11, 2019**

Related U.S. Application Data

(62) Division of application No. 29/626,452, filed on Nov. 17, 2017, now Pat. No. Des. 858,997.

(57) **CLAIM**

The ornamental design for a tracking module for an oral care implement, as shown and described.

DESCRIPTION

FIG. 1 is a front right perspective view of a tracking module for an oral care implement according to the new design;

FIG. 2 is a front view thereof;

FIG. 3 is a rear view thereof;

FIG. 4 is a right side view thereof;

FIG. 5 is a left side view thereof;

FIG. 6 is an enlarged top view thereof; and,

FIG. 7 is an enlarged bottom view thereof.

The broken lines illustrate portions of the article that form no part of the claimed design.

1 Claim, 4 Drawing Sheets
